[57] CLAIM

The ornamental design for a game board, as shown and described.

DESCRIPTION

FIG. 1 is a top plan view of a game board showing my new design; and,

FIG. 2 is a front elevational view thereof, with the rear, left, and right elevations being mirror images thereof.

The bottom of the present game board design is plain and devoid of ornamentation.

1 Claim, 2 Drawing Sheets

FIG. 1

FIG. 2
